UNITED STATES PATENT OFFICE

129,075

DESIGN FOR A DRESS

Jane Marchesa, Flushing, N. Y.

Application July 24, 1941, Serial No. 102,415

Term of patent 3½ years

To all whom it may concern:

Be it known that I, Jane Marchesa, a citizen of the United States, residing in Flushing, in the county of Queens and State of New York, have invented a new, original, and ornamental Design for a Dress, of which the following is a specification, reference being had to the accompanying drawing, forming part thereof.

I claim:

The ornamental design for a dress, substantially as shown,

JANE MARCHESA.
